Patented Oct. 16, 1973

228,600

COMBINED BOOK SUPPORT AND FILM STRIP HOLDER

Wesley Moffatt, 19 Oakwood Crescent,
Scarborough, Ontario, Canada

Filed Dec. 30, 1971, Ser. No. 172,957

Term of patent 14 years

Int. Cl. D6—06

U.S. Cl. D6—184

FIG. 1 is a perspective view of the combined book support and film strip holder; and

FIG. 2 is a side view of the same, the other side being a mirror image of the side which is shown.

I claim:

The ornamental design for a combined book support and film strip holder, as shown and described.
